His Attorney.

UNITED STATES PATENT OFFICE.

EMIL FALCKE, OF BERLIN, GERMANY, ASSIGNOR TO GENERAL ELECTRIC COMPANY, A CORPORATION OF NEW YORK.

MEANS FOR THROTTLING FLUID-PRESSURE-OPERATED DEVICES.

Application filed May 1, 1924, Serial No. 710,320, and in Germany May 12, 1923.

This invention relates to fluid pressure operated devices of the reciprocating type in which the movement of the piston is controlled by an exhaust valve and the invention has for its object the provision of improved means for automatically throttling the exhaust fluid from such devices to vary the operating speed of the piston.

While my invention is capable of general application to reciprocating pressure operated devices, it is of particular utility when applied to the pneumatic operating mechanism of a railway motor controller which is arranged to operate the controller through a sequence of definite steps to control one or more driving motors. In order to operate such a motor controller satisfactorily so that each step is quickly and accurately effected, it is desirable if not absolutely necessary that the pneumatic operating mechanism operate at a greater speed through the first part of each successive step than at the end of the step. For this purpose it has been proposed to use an additional valve in conjunction with the usual exhaust valve for controlling the pneumatic operating mechanism of such controllers and to arrange the additional valve so that it is automatically opened only at the beginning of each switching step. Such an automatically controlled auxiliary valve arrangement is described and broadly claimed in Patent 1,382,872, issued June 28, 1921, to John F. Tritle.

The present invention provides a more simple and less expensive automatic controlling means for permitting a high speed of the step by step pneumatic operating mechanism at the start of each step and gradually checking the speed of operation at the end of the step. Briefly speaking, this is accomplished by providing an exhaust conduit through which the fluid is exhausted from the pneumatic operating mechanism and which is so proportioned and designed that the initial throttling effect on the exhausting fluid is very slight, but gradually increases to check the speed of the operating mechanism. In this way when the pneumatic mechanism is connected to operate a railway motor controller, the quick initial movement of the pneumatic operating mechanism at the start of each step enables the total time interval required for changing the motor connections to be materially

reduced and also insures a quick break of the connections that avoids arcing or burning of the controller contacts. Furthermore, operation at the slower speed near the end of each step effectively prevents "over-shooting" or movement of the controller past the desired controlling position and thereby insures greater accuracy in the control of the motor circuits.

For a better understanding of my invention, reference is had to the following description taken in connection with the accompanying drawings in which Fig. 1 is a partial view in section of a fluid pressure operating mechanism embodying my invention, and Fig. 2 is an enlarged sectional view of certain parts thereof.

The novel features which I believe to be characteristic of my invention are set forth with particularity in the appended claims.

Referring to Fig. 1 of the drawing, the invention is shown as applied to one end of a well-known type of double acting pressure operating mechanism which comprises the cylinder 10 within which the piston 11 reciprocates to rotate the shaft 12 by means of the rack and pinion gearing shown. In the double-acting type of pneumatic mechanism shown the rack and pinion mechanism is held stationary by balancing the air pressure exerted on the right hand side of piston 11 against an opposing substantially constant pressure which is either applied to the left hand side of piston 11, or preferably to a second piston connected to the other end of the rack and operating in cylinder 10, as shown in the previously mentioned Tritle Patent No. 1,382,872. Hence, when the pressure is exhausted from the right hand side of piston 11 the opposing pressure predominates and moves the piston to the right a distance determined by the amount of fluid exhausted from the right hand side of piston 11. Thus, by successively exhausting pressure from the right hand side of the piston 11 the shaft 12 may be moved to and stopped in each of a series of definite positions. The shaft 12 may be connected to operate any desired apparatus (not shown) such for example as the operating cam shaft of a railway motor controller which it is desired to move in a step by step manner through a series of definite operating positions.

For controlling the movement of the pis-

ton 11, an electrically controlled valve 13 is provided for admitting operating fluid from the pressure line 14 through the chamber 15 into the right hand end of cylinder 10 and for exhausting the operating fluid from the cylinder 10 through the chamber 16 and the exhaust conduit 17 to atmosphere.

As shown more in detail in Fig. 2, the valve 13 is of the double acting type and is arranged to cooperate with the inlet port 18 and the exhaust port 19 formed in the valve casing 20 when raised or lowered through operation of the valve stem 21 in admitting and exhausting fluid pressure from the cylinder 10. It will be observed that the exhaust conduit 17 in the preferred form shown, comprises a pipe bent into a spiral or other similar space saving curved form and has one end connected to the chamber 16 and the other end open to atmospheric pressure. According to the present invention the relative length and cross-section of the exhaust pipe 17 are proportioned to effect a predetermined increase in throttling effect after the initial flow of exhaust fluid from cylinder 10. It will be evident that with a pipe of given area of cross section the length may be varied to produce the throttling effect desired. In order to protect the exhaust pipe 17 from harmful temperature influences it may be advantageous under some conditions to encase the pipe within the protective insulation covering 22. For example freezing of any moisture condensing upon the inner walls of the exhaust pipe 17 is effectively prevented. As the freezing of the moisture necessarily reduced the cross sectional area of the pipe, the protective insulating covering 22 serves to prevent variation in the throttling effect of the exhaust pipe due to this reduction in its cross sectional area.

As thus constructed and arranged the operation of my invention is as follows:

With valve 13 in the position shown, the right hand end of cylinder 10 is in direct communication with the pressure line 14 and hence the operating fluid in the cylinder 10 is at a pressure substantially the same as that in the pressure line 14. Under these conditions the opposing pressures on the piston 11 are balanced and the shaft 12 is held stationary. If the valve 13 is now operated from the position shown to that in which the inlet port 18 is closed, and the exhaust port 19 is opened, the fluid under pressure in the cylinder 10 is exhausted to the atmosphere through the chamber 16 and the exhaust conduit 17. Since the exhaust conduit is filled with air at atmospheric pressure at the time the exhaust port is opened, the initial flow of fluid from the cylinder 10 occurs very rapidly until the normal pressure gradient determined by the cross sectional size as well as the length of exhaust pipe is

established. During this interval the resulting movement of piston 11 to the right is at a substantially high rate of speed. However, as the pressure gradient of the exhausted fluid in the exhaust pipe 17 is established the throttling effect of the exhaust conduit 17 finally reaches a value which depends upon the relative length and cross section of the pipe 17, as previously pointed out. Thus the escape of air from the cylinder 10 is checked more and more as after the initial rush into the exhaust pipe 17 occurs, and the speed at which the piston 11 moves to the right is correspondingly decreased. After the piston 11 has moved the required distance to the right to bring the shaft 12 into the desired operating position further movement may be arrested almost instantly by operating the double acting valve 13 to close the exhaust port 19 and open the inlet port 18. In this way the piston 11 and, consequently, the shaft 12, may be stopped accurately at the desired operating position.

Further operation of the piston 11 and the shaft 12 to the next succeeding operating position is accomplished by again operating the valve 13 to close the inlet port 18 and open the exhaust port 19. Due to the sudden pressure equalization in the exhaust conduit 17, the piston 11 initially moves quickly and the subsequent throttling effect of the exhaust conduit again reduces the operating speed of the piston preparatory to reclosing the valve 13 to stop the piston accurately at the next succeeding position.

What I claim as new and desire to secure by Letters Patent of the United States is:—

1. In a fluid pressure operated device, the combination of a cylinder, a piston movable to an intermediate position therein, a valve for exhausting fluid from the said cylinder to control the movement of said piston to said position, and an exhaust conduit extending from said valve having a relative length and cross section such as to effect a predetermined increase in the throttling effect on the fluid exhausted upon the opening of said valve and thereby automatically decrease the rate of movement of the piston after a rapid initial movement thereof.

2. In a fluid pressure operated device, the combination of a cylinder, a piston movable therein, a valve for exhausting fluid from said cylinder to control the movement of said piston, and means comprising a pipe of relatively small cross section and substantial length for throttling the fluid exhausted upon the opening of said valve and thereby automatically retarding the movement of said piston after a rapid initial movement thereof.

3. In a fluid pressure operated device, the combination of a cylinder, a piston movable

therein, a valve for exhausting fluid from the said cylinder to control the movement of the said piston, means comprising a pipe of relatively small cross section and substantial length for throttling the fluid exhausted upon the opening of said valve to automatically decrease the rate of movement of the

piston after a rapid initial movement thereof, and a heat insulating covering for said pipe.

In witness whereof, I have hereunto set my hand this 12th day of April, 1924.

EMIL FALCKE.
